H. O. NIELSEN,
PERMUTATION PADLOCK,
APPLICATION FILED APR. 6, 1921.

1,408,771.

Patented Mar. 7, 1922.

UNITED STATES PATENT OFFICE.

HENRY O. NIELSEN, OF TREMONTON, UTAH.

PERMUTATION PADLOCK.

1,408,771.

Specification of Letters Patent.

Patented Mar. 7, 1922.

Application filed April 6, 1921. Serial No. 458,944.

To all whom it may concern:

Be it known that I, HENRY O. NIELSEN, a citizen of the United States, residing at Tremonton, in the county of Boxelder, 5 State of Utah, have invented certain new and useful Improvements in Permutation Padlocks; and I do hereby declare the following to be a full, clear, and exact description of the invention, such as will enable others skilled in the art to which it 10 appertains to make and use the same.

This invention relates to new and useful improvements in locks and particularly to permutation padlocks.

15 One object of the invention is to provide a permutation lock wherein the tumblers are so formed that the "feel" and "sound", whether the tumblers are in locking or unlocking position, will be the same, thereby preventing the unauthorized opening of the lock by tapping or trial turns of the tumblers.

20 Another object is to provide a permutation lock wherein there is provided a removable cap or cover for the body of the lock which can only be turned for removal when the shackle of the lock is in unlocked and withdrawn position.

25 A further object is to provide a permutation lock of the padlock type wherein the 30 detent, which holds the shackle within the body of the lock, is maintained in locking position, and is so constructed and positioned that the shackle may be readily and 35 easily slipped into the body and automatically engaged with the detent, whether the tumblers are in unlocked or locked position.

40 Other objects and advantages will be apparent from the following description when taken in connection with the accompanying drawing.

In the drawing:

45 Figure 1 is a side elevation of a permutation padlock made in accordance with the invention.

Figure 2 is a vertical sectional view through the lock, in locked position.

50 Figure 3 is a vertical sectional view through the lock in unlocked position, the shackle being shown as withdrawn.

Figure 4 is a horizontal sectional view through the lock, on the line 4-4 of Figure 2, passing in a plane just above the hori-

zontal portion of the detent, the shackle 55 flexing the detent.

Figure 5 is a perspective view of the detent.

Figure 6 is a perspective view of one of the tumblers.

Referring particularly to the accompanying drawing, 10 represents a metal body of cylindrical shape and having a flanged head 11 on one end, and flanged cap 12 on its other end, the latter being secured to the body by means of the screw stem 13 carried by the inner face of the cap. In the inner face of the cap, at one side of the screw stem, is a recess 14, the purpose of which will appear later herein. Rotatably engaged on the body are the three tumbler rings 15, each having on its outer peripheral face a series of numbers or letters, with adjacent marks adapted to register or align with similar marks on the flanges at the ends of the body, when the proper permutation is made to open the lock. Formed in the inner face of each ring or tumbler are the transverse grooves 16, and 17, the former being deeper than the latter and being arranged, each opposite a number or letter on the periphery of the ring, while the other or shallower grooves are disposed intermediate the deeper grooves and letters or numbers. In the drawings there are shown three rings, but this number may be increased or diminished as desired.

Formed longitudinally through the body adjacent one side thereof, is a circular opening or bore 18, while a shorter circular bore 19 is formed adjacent the diametrically opposite side of the body. The upper end of the longer bore 18 is disposed in registry with the before mentioned recess 14, formed in the lower face of the cap plate 12. Formed transversely through the body, and communicating at its opposite ends with the bores 18 and 19, is a bore or passage 20, in which is disposed a coil spring 21. Formed vertically in the side of the body, at one side of the bore 18, is a longitudinally extending recess 22, and communicating with the lower end of this recess, and extending transversely through the body, in a plane at the inner end of the flanged head 11, is an angular passage 23, the inner end of said passage communicating with a shorter bore 19, as clearly

seen in the sectional views Figure 2 or 3. Disposed in the vertical recess and the passage 23 is an L-shaped detent 24, the horizontal leg of which has a beveled nose 25 which normally enters the bore 19. The vertical leg of the detent 24 is adapted to enter certain of the deeper notches 16, when in vertical alignment. One end of the coil spring 21 is secured to the vertical leg of 10 the detent while its other end is secured to the opposite side of the bore 19.

A shackle is provided for the lock and includes the bight portion 26, and the legs 27 and 28, the former of which is considerably longer than the other and is disposed in the longer bore 18 of the body of the lock, while the latter or shorter leg is disposed in the shorter bore 19. The inner end of the leg 27 is formed with a head 29 which is adapted to engage with a lug or projection 30, on the lower portion of the detent, whereby to prevent the complete withdrawal of the shackle when in unlocked position, as shown in Figure 3. The inner end of the shorter leg 28 is formed with a notch 31, which receives the nose 25 of the horizontal leg of the detent 24. The side of the inner end of the leg 28 is beveled, as shown at 32, and the said horizontal leg of the detent is flexible, 30 whereby, when the shackle is pushed into the body, this beveled end of the leg 28 will flex the said leg of the detent to one side, thereby not causing any sliding movement of the detent toward the grooves of the tumbler 35 rings. The upper wall of the notch 31 is beveled and rests on the beveled face of the nose of the detent, whereby when the proper deeper notches 16 are in alignment, and an outward pull is exerted on the shackle, the 40 said beveled wall of the notch will ride on the beveled face of the nose and cause the detent to slide over and dispose its vertical leg within the said aligned notches 16. Immediately that the shorter leg of the shackle 45 is withdrawn from the body of the lock, the spring 21 returns the detent into its normal locking position, that is with its nose within the shorter bore, ready for flexing by the shorter leg 28 of the shackle. As soon as the 50 shorter leg of the shackle has passed into the bore 19, to such a distance that the notch 31 is opposite the nose of the detent, the horizontal leg of the detent immediately springs over to engage the nose in the said notch. 55 By reason of the flexibility of the horizontal leg of the detent, the shackle can be pushed into the body of the lock, whether the deeper notches of the tumbler rings are in alignment or not, thus rendering the 60 proper engagement of the shackle by the de-

tent, thus obviating the necessity of holding the shackle in position while the tumbler rings are rotated into locking position.

Attention is also directed to the recess in the removable cap into which the upper end 65 of the longer leg of the shackle engages, when the shackle is in locked position. It will be noted that the cap cannot be rotated, for removal, while the lock is locked, it being necessary to unlock the device, withdraw 70 the shackle, before the cap will be free to rotate.

What is claimed is:

1. A permutation lock comprising a body 75 having a bore therethrough and a second bore partly therethrough, a shackle having a longer leg and a shorter leg disposed respectively in the first and second bores of the body, the shorter leg having a notch, a spring held detent engaging in the notch of 80 the shackle, means on the detent for engagement with the longer leg to prevent complete withdrawal of the shackle from the body, rotatable tumblers on the body, the detent being bodily movable by the shackle 85 upon movement of the shackle into unlocked position, and having a portion thereof arranged to be flexed by the shackle in a direction at right angles to the first movement.

2. A permutation lock comprising a body, 90 a slidable shackle in the body, permutation tumblers on the body, and a detent for releasably holding the shackle within the body and preventing complete withdrawal thereof 95 from the body, said detent being resiliently held in engagement with the shackle and being arranged to be moved bodily when the shackle is withdrawn and to be flexed upon movement of the shackle into the body.

3. A permutation lock comprising a body 100 and a shackle slidably and pivotally engaged in the body, a plurality of notched permutation tumbler rings rotatable on the body, and an L-shaped detent mounted in the body and normally spring pressed into engagement with the shackle, said detent having its horizontal portion arranged to be engaged by the said shackle and to be moved bodily 105 into aligning notches of the tumbler rings, and to have its horizontal portion flexed in a plane at right angles to the bodily movement by the shackle upon inward movement of the shackle.

In testimony whereof, I affix my signature, in the presence of two witnesses.

HENRY O. NIELSEN.
